ELECTRIC HEATING

Robert H. Park, Pembroke, Mass.

Application December 12, 1931, Serial No. 580,533

14 Claims. (Cl. 219—20)

This invention relates to electric heating, and the object is to provide an improved mechanism wherein the object to be heated, for example, a liquid-containing vessel, is included as a part of a circuit of high amperage and low voltage.

My invention will be well understood by reference to the following description of the specific embodiment thereof shown by way of example in the accompanying drawings, wherein:

10 Fig. 1 is a plan view of a stove such as would be used for domestic cooking purposes;

Fig. 2 is a section through the top of the stove and the vessel thereon taken on the line 2—2 of Fig. 1 and showing parts beneath in elevation;

15 Fig. 3 is a similar view of the parts shown in Fig. 2 as seen from the left of that figure.

Fig. 4 shows certain parts of Fig. 2 dissociated from adjacent mechanism;

Fig. 5 is a detailed section on an enlarged scale 20 on the line 5—5 of Fig. 3;

Fig. 6 is a section on the line 6—6 of Fig. 3;

Fig. 7 is a section on an enlarged scale on the line 7—7 of Fig. 6; and

Fig. 8 is a wiring diagram.

25 Electric heating appliances for cooking purposes are commonly used wherein the heat is derived from a resistance wire heated to incandescence. While such heating elements are satisfactory for baking, broiling and the like, they are slow and uneconomical for such operations as boiling, and in the construction about to be described (see Fig. 8) a liquid containing vessel 9, such as a saucepan, is included as a part of a circuit 11 of high amperage and low voltage which may be the secondary circuit of the transformer 13, of which the primary coils 15 may be energized from a source of relatively high voltage, such, for example, as the ordinary 110 volt electric lighting mains. A current of high heating capacity is thus passed directly through the pan, heating the liquid therein rapidly and efficiently. To exclude current from the contents of the pan with possible electrolytic action thereon I prefer to provide the pan with an enamel lining 16. The bottom of the saucepan 9 may be provided with downwardly projecting, prong-like contacts 17 which may be firmly engaged by clamping jaws 18 (see Fig. 2) to connect the pan in the circuit.

30 Means, preferably power means, are utilized to close the clamps and, after they are closed, to initiate the current supply. When the heating operation is completed, the supply circuit is preferably opened and then the clamps are released. I will first describe the operation in a general way with reference to the diagram, Fig. 8, and then,

with reference to the other figures, the mechanical construction herein shown by way of example.

Referring, therefore, to Fig. 8, the pan 9 being placed in position with the contacts 17 between the open jaws 18 of the clamps to permit the latter to be closed thereon, the heating operation may be started by moving the double pole switch 21 to the left in the figure to engage the contact 23. Current is thus supplied through wire 24 and bridge 25 to an electric motor 27 which by mechanical means (not shown in the diagram) closes the clamps 18. When the clamps are closed, movement of the motor initiates the flow of current to the transformer 13, and herein a cam 29 driven by the motor closes switch 31 energizing 15 the solenoid 33. The core of this solenoid rising causes bridge 35 to close the circuit to the primary 15 of the transformer. It also lifts bridge 25, breaking the circuit to motor 27, stopping the same, and lifts bridge 37 in the conductor leading 20 to a motor magnet 39 so that the latter cannot receive current while the solenoid is energized. The number of turns in the primary and consequently the rate of heating may be controlled in the usual manner by a controlling switch 41. 25

When the heating is completed, switch 21 is moved over into contact with the pole 43. By this means the circuit of solenoid 33 is broken and bridge 35 falls, interrupting the current to the primary 15. As bridge 37 closes, current 30 flows through pole 43 to the motor magnet 39, the operation of which provides by means hereinafter to be described for the release of clamps 18 and also for the reopening of switch 31.

Referring now to Fig. 2, the contacts 17 are there shown as passing through suitable openings 45 (see Fig. 1) in the stove top 47 beneath which openings the clamping jaws 18 are arranged. These jaws may take the form shown in Fig. 5 and may comprise suitable contact blocks 49 40 mounted between side members 51 pivotally mounted on rock shafts 53 and yieldably connected thereto by means of the strong torsional springs 55 which yield when the blocks are pressed against the contacts 17. The block 49 may be laterally extended as shown in Fig. 3 to provide for connection of the flexible conductor 57 thereto. The side surface of the block 49 makes the electric contact and I preferably provide an insulating covering 59 over the top face of the jaw to avoid any possible inefficient closing of the circuit by engagement of the bottoms of the contacts 17 with the tops of the jaws. 50

Referring to Fig. 2, the rock shafts 53 for the pairs of contacts are preferably intergeared by 55

pinions as shown whereby on turning of one shaft the pairs of clamping jaws will open and close, as will be well understood. The clamping jaws are normally open and herein I have shown 5 one shaft as provided with the crank arm 61 which is acted upon by spring 63 normally tending to rock it counterclockwise, viewing Fig. 3, and to open the clamps. To close them against the operation of the spring, crank arms 65 on 10 certain of the shafts 53 may be connected by links 67 forming a toggle which carries at its central pivot a cam follower 69. Movement of this follower upwardly to the position shown in Fig. 2 will cause the clamps to close. The toggle is 15 herein straightened by the cam 71 on cam shaft 73 driven at suitable speed from motor 27 already referred to in the description of the wiring diagram. It will be seen that if the cam 71 is turned from the position shown in Fig. 2, it will engage 20 the follower 69 and gradually raise it to the point there shown, but when the nose of the cam passes the follower, if no other mechanism is provided the follower would be free to fall and the clamps would be opened and released on each revolution 25 of the cam shaft. I therefore provide a member 75, best shown in Fig. 4, having the portion 77 of substantially the same radius as the highest portion of the cam and yieldably connected to the cam 71 by means of spring 79 which normally 30 tends to hold the member 75 rotated clockwise from the position of Fig. 4 with its stop shoulder 81 in contact with pin 83 projecting from the cam and with the part 77 in alignment with the highest or nose portion of the cam. The member 75 35 is also provided with a projecting pin 85 adapted to engage a lug 87 on a pivoted arm 89 normally held by means of spring 91 in the position shown in Fig. 4 with lug 87 in the path of pin 85 but which may be depressed by means of the motor 40 magnet 39, as will hereinafter be described. In the operation of the parts, therefore, when the high part of the cam, the member 75 moving therewith, brings the toggle to the position shown in Fig. 2, pin 85 makes contact with stop 87 and 45 stops further movement of the member 75, the cam, however, continuing to move and tensioning spring 79. The part 77, therefore, remains stationary under the follower 69 and holds the clamps closed even after the nose of the cam 71 passes beyond the follower to the position shown 50 in Fig. 2.

Cam shaft 73 may also be provided with a 55 tappet or cam 93 adapted, when the parts reach the position shown in Fig. 2, to operate a snap switch 31 which may be of the type shown in the patent to De Reamer 1,579,082, March 30, 1926, and unnecessary to illustrate or describe in detail. This switch is here shown as carried on a pivoted arm 95 connected by rod 97 to crank arm 61. Thus, 60 when the toggle formed by arm 67 is moved toward the position of Fig. 2 to close the clamps, arm 61 consequently is swung clockwise and arm 95 is lifted to bring the switch into the path of cam 93.

65 It will thus be seen that when switch 21 is moved onto the contact 23 and the motor 27 energized, cam 71 starts to turn. When it has reached a position about 35° short of that shown in Fig. 2, the highest point of the cam has acted 70 on follower 69 and closed the clamps which are held in that position by the action of the surface 77 as described. Meanwhile switch 31 has been brought into the path of the cam 93, and when the cam shaft reaches the position shown in 75 Fig. 2, that switch is thrown, energizing (see Fig.

8) solenoid 33, initiating the flow of current to the heating element and by the lifting of bridge 25 breaking the circuit to the motor so that the cam shaft 73 stops in the position shown. When the heating is completed, if the switch 21 is moved to the off position in contact with pole 43, the circuit of the solenoid 33 is broken as before described. The core of solenoid 33 falls and the bridge 35 breaks the circuit to the primary 15 of the transformer. The circuit of motor magnet 39 is closed at 43 and 37, the magnet attracts its armature, pulling down arm 89, releasing the member 75 to spring 79 so that the surface 77 is drawn out from beneath the cam follower, releasing the rock shaft to the action of spring 63 (Fig. 2) and opening the clamps. In this opening movement arm 95 swings downwardly, removing switch 31 from the nose of cam 93 and permitting the same to snap open. This action, while a rapid one, permitting the cooking vessel 20 to be immediately removed, is nevertheless delayed until after the heating circuit is broken since motor magnet 39 cannot be energized until bridge 37 is closed and bridge 35 opened on de-energizing of the solenoid 33. The possibility of 25 arcing is thus avoided.

Referring again to Fig. 8, I have there shown means to open the heating circuit in case the resistance abnormally rises, as might happen, for instance, when a boiling operation was in question and the pan boiled dry and became red hot. For this purpose I interpose in the circuit of solenoid 33 a safety switch which may comprise a fixed contact 99 with which cooperates a spring blade 101 connected in the circuit by means of 30 a flexible lead 103 and carried by a rocking beam 105 pivoted at 107 and having the spring 109 attached thereto through a suitable lever arm as shown so as to hold the beam tilted either in the closed position of the switch as shown 40 or in the open position when the beam has rocked somewhat clockwise. A handle 111 on the beam provides for returning the switch to the closed position shown after it has been opened in the manner about to be described. Opposite ends 45 of the beam are here shown as connected to the cores of coils 113 and 115 respectively, the conjoint action of which on their respective cores controls the position of the beam. Coil 113 is arranged in series in the circuit of the primary 50 coils 15 of the transformer and is so wound as to attract its core with a force proportional to the current (amperage). Coil 115, however, is of high resistance and may be bridged across a 55 portion of the coil 115, conveniently with the addition of a resistor 117, and acts on its core with a force proportional to the electro-motive force or voltage. Consequently when the resistance of pan 9 rises, the current demand of the secondary falls, current (amperage) in primary 15 decreases, the electro-motive force increases, and the force of coil 115 overcomes the force of coil 113, rocking beam 105 clockwise and opening the switch.

It will be seen that the safety switch 99—101, 65 the operation of which has just been described, is disposed in the lead from pole 23 of switch 21 before conductor 24 branches therefrom and consequently the switch also controls the circuit of the motor 27.

Referring to Figs. 2, 3 and 6, I prefer to provide the pan 9 with a depending marginal flange 119 substantially equal in depth to the contacts 17 which project downwardly from the bottom so that the pan can be set securely upon any even 75

surface. To receive this flange the top of the stove may be provided with a suitable groove 121, the margins of which are preferably bevelled so that in the operation of placing the pan on the 5 stove its positioning with the contacts 11 presented to openings 45 is facilitated. The flange 119 is preferably made discontinuous, as shown in Fig. 6, preferably being broken at diametrically opposite points, and the groove is likewise 10 broken (see Figs. 6 and 7) by means of projections 123 adapted to be received in the discontinuities of the flange. The notch in the flange and the sides of this rib may similarly be 15 bevelled to facilitate positioning. It will be understood that these notches and ribs facilitate the angular positioning of the pan so that the contacts 11 may easily be passed through the 20 openings 45. These guiding parts are situated at the exterior easily visible and do away with any need of fumbling in placing the pan in position.

In the case of a domestic heating stove, such as shown in Fig. 1, besides the usual baking oven and broiler at 125 I may provide stations, herein 25 the two shown at the bottom of the figure, constructed as described for boiling or like operations involving the heating of relatively large quantities of material, and also stations such as those shown at the rear of the figure with resistance heating elements 127 of customary type 30 adapted to be heated by the ordinary current. I prefer to arrange these heating elements in such manner that openings 45a and grooves 121a similar to the openings 45 and grooves 121 are 35 provided in the stove top. This permits utensils primarily adapted for use for boiling purposes on the stations in front to be placed on or used in connection with the other heating elements. It 40 will be understood that the openings 45a are or may be dummies with no mechanism such as that shown in Fig. 2 beneath them.

I am aware that the invention may be embodied in other specific forms without departing from the spirit or essential attributes thereof, 45 and I therefore desire the present embodiment to be considered in all respects as illustrative and not restrictive; reference being had to the appended claims rather than to the foregoing description to indicate the scope of the invention.

50 I claim:

1. An electric heating device comprising a line 55 having clamps for engaging contacts on a device to be heated to include the same in an electric circuit, means to supply current of high amperage and low voltage to said line, a manually operable controlling switch, a motor and a relay having circuits passing through one pole of the 60 switch, a second switch in the relay circuit, mechanical means operated by the motor for closing the clamps, means operated by the motor for closing the second switch, a second motor having a circuit passing through another pole of the controlling switch, means operated by said 65 second motor for releasing the clamps, switches operated by said relay for the current supply to the heater and for the circuits of said motors, the latter being open when the first is closed and vice versa.

2. In an electric heating device of the kind 70 described, intergeared rock shafts carrying clamping jaws to engage contacts on a vessel, an arm on one of the shafts and a cam to act on the arm to close the jaws.

3. In an electric heating device of the kind 75 described, intergeared rock shafts carrying

clamping jaws to engage contacts on a vessel, an arm on one of the shafts, a switch for controlling the supply of current to said clamp, a cam shaft having both a cam to act on said arm and a cam controlling said switch. 5

4. In an electric heating device of the class described, intergeared rock shafts carrying clamp jaws, means for normally rotating the same to release the clamps, an arm for rotating the same to close the clamps, a cam shaft having a cam for swinging the arm, a support for said arm spring-connected to said cam, and a releasable stop for said support. 10

5. In a device of the class described, intergeared rock shafts carrying clamp jaws, means for normally rotating the same to release the 15 clamps, an arm for rotating the same to close the clamps, a cam shaft having a cam for swinging the arm, a support for said arm free on the shaft but spring-connected to said cam, a switch-operating cam on the shaft, a switch, a movable 20 support for the switch connected to the jaws and moving into the path of said latter cam when the jaws close, and a releasable stop for said support. 25

6. In a device of the kind described, in combination with contact-engaging clamps, means normally tending to open the same, an arm for closing the same, a cam for swinging said arm, a support for said arm spring-connected to said cam, and a releasable stop for said support. 30

7. In a device of the kind described, in combination with the contact-engaging clamps, means normally tending to open the same, an arm for closing the same, a cam shaft having a cam for swinging the arm, a support for said arm free on the shaft but spring-connected to said cam, a switch-operating cam on the shaft, a switch, a movable support for the switch connected to the jaws and moving into the path of said latter cam when the jaws close and a releasable stop for said support. 35 40

8. An electric heating device comprising a line having clamps for engaging contacts on a device to be heated to include the same in an electric circuit, means to supply current of high amperage and low voltage to said line, said clamps being normally open when the line is dead whereby said contacts may be freely positioned between the same without impediment, power means for closing the clamps, energy-storing 45 means operated by said power means, and means to release the clamps to the action of said energy-storing means for rapidly separating the same. 50

9. Equipment for electric cooking comprising 55 a self-contained portable vessel adapted to receive material to be heated and having studs projecting exteriorly therefrom, electric heating means incorporated in the vessel for which heating means said studs constitute terminals, a support for the vessel, pairs of relatively movable 60 clamp jaws positioned adjacent the support and connected respectively to opposite sides of a source of electric energy whereby when the pairs are closed on the studs respectively the said heating means forms a part of a circuit extending from one pair to another, said jaws having an open position wherein by a mere movement of superposition of the vessel on the support they 65 freely receive the studs between them with clearance between the parts, and means for closing and opening the jaws and for energizing and de-energizing the circuit interrelated to exclude energization of the circuit prior to the closing of the jaws and to effect deenergization thereof 70 75

- prior to opening of the jaws, the closing of the jaws and the deenergization of the circuit being initiated by separate manual operations.
10. Equipment for electric cooking comprising a self-contained portable vessel adapted to receive material to be heated and having studs projecting exteriorly therefrom, electric heating means incorporated in the vessel for which heating means said studs constitute terminals, a support for the vessel, pairs of relatively movable clamp jaws positioned adjacent the support and connected respectively to opposite sides of a source of electric energy whereby when the pairs are closed on the studs respectively the said heating means forms a part of a circuit extending from one pair to another, said jaws having an open position wherein by a mere movement of superposition of the vessel on the support they freely receive the studs between them with clearance between the parts, and means responsive to a manually effected operation for closing the jaws and effective only after such closure to permit energization of said circuit and means responsive to an independent manual operation for deenergizing the circuit and effective only after such deenergization to permit opening of the jaws.
11. Equipment for electric cooking comprising a self-contained portable vessel adapted to receive material to be heated and having studs projecting exteriorly therefrom, electric heating means incorporated in the vessel for which heating means said studs constitute terminals, a support for the vessel, pairs of relatively movable clamp jaws positioned adjacent the support and connected respectively to opposite sides of a source of electric energy whereby when the pairs are closed on the studs respectively the said heating means forms a part of a circuit extending from one pair to another, said jaws having an open position wherein by a mere movement of superposition of the vessel on the support they freely receive the studs between them with clearance between the parts, and means responsive to independent manual operations respectively for sequentially closing the jaws and energizing the circuit, and for sequentially deenergizing the circuit and opening the jaws.
12. Equipment for electric cooking comprising a self-contained portable vessel adapted to receive material to be heated and having studs pro-
- jecting downwardly therefrom, electric heating means incorporated in the vessel for which heating means said studs constitute terminals, a support for the vessel having openings of relatively large size freely to pass the studs, pairs of relatively movable clamp jaws beneath the openings and connected respectively to opposite sides of a source of electric energy whereby when the pairs are closed on the studs respectively the said heating means forms a part of a circuit extending from one pair to another, said jaws having an open position wherein by a mere movement of superposition of the vessel on the support they freely receive the studs between them with clearance between the parts, and means responsive to independent manual operations respectively for sequentially closing the jaws and energizing the circuit, and for sequentially deenergizing the circuit and opening the jaws.
13. Equipment for electric heating comprising a self-contained portable vessel adapted to receive material to be heated and having studs projecting downwardly from its bottom, electric heating means incorporated in the vessel for which heating means said studs constitute terminals, a support for the vessel, pairs of relatively movable clamp jaws positioned adjacent the support and connected respectively to opposite sides of a source of electric energy whereby when the pairs are closed on the studs respectively the said heating means forms a part of a circuit extending from one pair to another, said jaws having an open position wherein by a mere movement of superposition of the vessel on the support they freely receive the studs between them with clearance between the parts, cooperating means on the support and vessel respectively for centering and orienting the vessel on said support to facilitate insertion of the studs between the open jaws and manually operable means for closing the jaws and energizing the circuit and also for deenergizing the circuit and opening the jaws.
14. An electric heating device comprising a line having clamps for engaging contacts on a device to be heated to include the same in an electric circuit, means to supply current of high amperage and low voltage to said line, and means mutually exclusive in their operation for opening and closing the clamps.

ROBERT H. PARK. 50
